UNITED STATES PATENT OFFICE.

RICHARD SMITH DAHL, OF CHARLOTTENLUND, NEAR COPENHAGEN, DENMARK.

ELECTRICAL COMMUTATOR.

1,362,084.

Specification of Letters Patent. Patented Dec. 14, 1920.

Application filed October 27, 1919. Serial No. 333,732.

To all whom it may concern:

Be it known that I, RICHARD SMITH DAHL, subject of the King of Denmark, residing at Charlottenlund, near Copenhagen, Denmark, have invented new and useful Improvements in Electrical Commutators, of which the following is a specification.

The invention is an arrangement in electrical commutators by which the commutator segments and the insulating layers between the latter are held together by means of projecting flanges on a core or bush of insulating material, which is shaped under high mechanical pressure, it being in liquid or pulverized state pressed into the cavity formed by the segments when the latter are placed side by side in the shape of a ring, the insulating mass in the said cavity hardening or solidifying so as to become a compact hard core fitting tightly against the segments and forming the hub or sleeve of the commutator, and the distinguishing feature of the invention is that the segments encircle the flanges on the commutator sleeve which serve to fasten them and hold them together, the said flanges fitting into and being formed in suitably shaped, for instance dove-tailed or T-shaped recesses in the segment edges facing the commutator shaft.

By this construction of commutators the advantage is attained that the security against fracture of the commutator sleeve while the commutator is used becomes considerably greater than by the heretofore known commutators of this kind by which the flanges serving to hold the segments in position encircle the segments, in so far as they fit into wedge-shaped notches at the segment ends in the same manner as the clamping rings on commutators of ordinary known kind. The said flanges get thereby a shape which causes the flanges, during the rotation of the commutator to be exposed to very forcible tension and bending, so that they frequently burst by action of the centrifugal force. This is especially the case with commutators of considerable length, it being never possible, by the heretofore used constructions, to use more than two, and for that matter never less than two, flanges to keep each commutator together, and the strain on each of the flanges will therefore increase largely with the length of the commutator. In case of the commutator constructed according to the present invention, on the contrary, there may be used either one

single segment-fastening flange or several distributed along the entire length of the commutator.

On the drawings, Figures 1 and 2 show longitudinal sections of two different constructions of the invention.

Fig. 3 is a fragmentary transverse section through the middle of Fig. 2.

In the construction shown in Fig. 1, each segment 2 and equally each insulating layer 12 has, on the edge facing the shaft 1, only one single and, in the construction shown, essentially T-shaped recess, wherein the circular flange 3 on the commutator sleeve 4, which serves to hold the segments together is formed by liquid or pulverized insulating material, for instance bakelite, being pressed into the cavity produced within the ring formed by the commutator segments being joined together in known manner.

In the construction shown in Fig. 2, each segment 2 and insulation 12 is fitted with several T-shaped recesses on the edge facing the shaft, so that a corresponding number of circular fastening flanges 3 for the segments are formed. If these, as shown, are distributed evenly along the commutator, any outward bulging of the central portion of the segments due to rotation of the commutator will be effectively prevented.

When centrifugal force is acting, the flanges 3 will be exposed to radially directed tensile and shearing stresses. Of these the tensile stress is the one against which the insulating material offers the lesser resistance, but by the shape and construction of commutators here specified the advantage is attained that the flanges may always be made so wide that the tensile stress may always be kept within the permissible limit, even in case of very high rotary speeds.

The portions of the sleeve 4 which are most exposed to fracture are those located nearest to the end faces thereof. These sleeve-portions may be reinforced considerably, as shown in Figs. 1 and 2, by letting the segment ends form, on the side facing the shaft 1, two inwardly directed and toward one another slanting lugs 5 and 6, whereby there will be produced, on the ends of the commutator sleeves, two circular reinforcing flanges 7 located between the said lugs on the end faces of the commutator.

The sleeve 4 may be fastened either, as shown in Fig. 1, directly on the shaft of the motor concerned or, as shown in Fig. 2,

on a separate hub 8 of suitable known construction.

Having now particularly described and ascertained my said invention and the manner in which the same is to be performed, I declare that what I claim is:—

1. A commutator comprising an annular series of insulated commutator bars, having end portions extending toward the center, 10 undercut on their sides toward the middle, and a body of molded insulating compound holding the bars in place, said insulating body being formed with an annular flange on its outer circumference engaging toward 15 opposite ends the undercut portions of said bars.

2. A commutator comprising an annular series of commutator bars, insulating layers alternating with and located between the 20 bars, said bars and layers having end portions extending toward the center, undercut on their sides toward the middle, and a body of molded insulating compound, holding said bars and layers in place, said insulating body being formed with annular flanges near 25 its opposite ends engaging the undercut portions of such bars and layers.

3. A commutator comprising an annular series of commutator bars and insulating 30 layers alternating therewith, said bars and layers extending from end to end of the commutator and having their ends extended

toward the center and undercut on their sides toward the middle, and a body of molded insulating compound within the bars 35 and layers, having, near opposite ends, annular flange portions whereby to hold said bars and layers in place.

4. A commutator comprising commutator bars and intervening insulating layers, 40 formed at their opposite ends with portions projecting obliquely inwardly and toward each other, combined with a body of molded insulating compound within the bars and layers, having an annular flange portion en- 45 gaging such projecting portions.

5. A commutator comprising an annular series of commutator bars and intervening insulating layers, extending from end to end of the commutator, said bars and layers having at their ends undercut portions projecting inwardly toward each other, and having between them undercut portions projecting inwardly, and a body of molded insulating compound filling the space within the bars 50 and layers and engaging the undercut portions thereof.

In witness whereof I have hereunto signed my name in the presence of two subscribing witnesses.

RICHARD SMITH DAHL.
